UNITED STATES PATENT OFFICE.

EDWARD E. PARSONAGE, OF MOLINE, ILLINOIS, AND CHARLES B. CRUTCHFIELD, OF TRENTON, KENTUCKY, ASSIGNEES TO DEERE AND COMPANY, OF MOLINE, ILLINOIS, A CORPORATION OF ILLINOIS.

COMBINED FOOTBOARD AND WAGON BOX.

Application filed April 5, 1920. Serial No. 371,177.

To all whom it may concern:

Be it known that we, EDWARD E. PARSONAGE, residing at Moline, in the county of Rock Island and State of Illinois, and CHARLES B. CRUTCHFIELD, residing at Trenton, in the county of Todd and State of Kentucky, have invented certain new and useful Improvements in Combined Footboards and Wagon Boxes, of which the following is a specification, reference being had thereto in the accompanying drawing.

Our invention relates to wagons and more particularly to necessary fixtures therefor, and the object of our invention is to simplify and economize the construction and attachment of such fixtures.

Referring to the drawings in which similar numerals indicate identical parts—

Figure 1 is a perspective view of the front end of a wagon body embodying my improvement, and

Figure 2 is a section on the line 2—2 of Figure 1.

The wagon body is of a well known construction and includes side boards 1 and front end boards 2 secured together by rods 3 and 4 in a manner well known in the art. Ordinarily, when the driver of the wagon is sitting, a seat (not shown) is supplied and a foot board 5 is necessary, this foot board 1 hinge to the rod by straps 6 secured to the foot board 5 and having their rear ends bent to loosely encircle the rod 4 so that the foot board 5 can be freely raised or lowered. Beneath the footboard 5 is a box 7 rigidly secured to the wagon body and having its upper edge declined rearwardly. Upon

this upper edge the footboard 5 normally rests to not only provide a rest and a brace for the feet of the driver but to operate as a cover for the box 7 in which tools or other property can be carried. The box 7 is a trapezium in cross section, but we do not limit ourselves to this form as other forms may be employed as far as the body of the box is concerned and to which our invention of a top or cover, declining from the front of the box to the wagon body, is employed and utilized as a foot rest.

It is common to provide a box secured to the wagon body but with its top edge declined from the wagon body and having a separate cover, in my construction, as explained, the upper edge of the box is declined rearwardly and we utilize the footboard as a cover, combining the utility of both, and reducing the cost of construction and simplifying it at the same time.

What we claim is—

1. The combination with a wagon body, of a box secured on the front thereof having its upper edge inclined forwardly and upwardly with respect to a horizontal plane, and a foot board mounted on the wagon body and forming a top for the box.

2. The combination with a wagon body, of a box secured on the front thereof having its upper edge inclined forwardly and upwardly with respect to a horizontal plane, and a top for said box hingedly secured on the wagon body and operating as a foot rest and brace.

EDWARD E. PARSONAGE.
CHARLES B. CRUTCHFIELD.
